Patented May 17, 1927.

UNITED STATES PATENT OFFICE.

MORRIS KATZ, OF NEW YORK, N. Y.

APRON.

Application filed April 28, 1925. Serial No. 26,327.

My invention relates to aprons made of paper or like material and has for its object to improve the same by providing a construction which will serve to better maintain the shape of the apron and also give the same increased strength at points where it is subjected to greatest strains. This object is attained by the novel construction hereinafter described in connection with the accompanying drawings and more particularly pointed out in the appended claims.

Referring now to the accompanying drawings—

Fig. 1 is a front view of an apron made in accordance with my invention.

Fig. 2 is a rear view of the upper part of the apron with the left side thereof in blank form and the right side thereof in finished form.

Fig. 3 is a sectional detail on the line 3—3 of Fig. 2, showing the wrinkled or crepe form of the paper from which the apron is made.

The apron here shown is of the bib type, comprising the body or skirt portion 1, having the strings 2 for fastening about the wearer's waist, and the integral bib portion 3 having a neck string 4 in loop form to be passed over the head.

There are many more or less temporary uses for aprons which make it desirable to produce them in both cheap and attractive forms. With such desiderata in view, aprons have been made of paper, both plain and fancifully designed. It has been found in practice, however, that aprons made of paper tear easily under slight strains and particularly so if they become wet or damp. It has been further found that these paper aprons readily tear at the points of attachment therewith of the fastening strings adjacent the corners between the waist and side lines, which points are subjected to the greatest strains because of the pulling effect of the apron strings; and even though the paper withstands the pulling effect of the strings without tearing, it nevertheless is liable to become distorted and weakened at such points after some little use.

In accordance with my invention, I form the apron from a so-called "crepe" paper which, as well known, is wrinkled in one

direction thereof as most clearly shown in Fig. 3. By making up the apron with the folds or wrinkles extending longitudinally of the apron, i. e. in the direction of its length, they permit of the apron stretching in the direction of its width, which is the only direction in which the apron is subjected to strains, without tearing or other injury.

As a means for maintaining the shape of the apron and also giving the same increased strength at the points where the fastening strings 2 are attached thereto, I provide the apron at the corners between the waist and side lines thereof with reinforcing sections 5 of substantially triangular form, which are preferably made by folding in a part of the paper blank from which the aprons are made.

In making up the aprons, a blank of substantially rectangular form is first cut, and this is provided at the upper or bib end thereof with two slits to provide the central bib portion 3. The two outer corner sections are then folded down upon themselves to provide the reinforcing sections 5.

Fig. 2 at the left-hand side thereof shows one of the corner portions in blank form, the slit separating it from the central bib being indicated at 6. This corner portion may be folded upon itself to provide the reinforcing section in any suitable or desired way. In the present case, I fold the same on the center line *a* to bring the upper half *b* back onto the lower half *c*. This brings the angular folding line *d* of the upper half opposite the angular folding line *e* of the lower half. The superposed corners *f* and *g* are then turned or folded over on the lines *d* and *e* onto the opposite superposed corners *h* and *i*, after which the several folds or plies are bent on the line *j* down onto the body of the apron, as shown at the finished right-hand side of the apron in Fig. 2.

After the apron blank has been folded at both corners in the manner described in connection with the left-hand corner thereof, it is run through a trimming and sewing machine to complete it in the manner shown, the trimmer of the machine operating to trim the edge of the apron and round off the square corners thereof and the sewing mech-

anism finishing and reinforcing the edge of the apron with a line of edge-stitching as at 7.

The sections 5, folded in the manner described, are of substantially triangular form. When the apron has been stitched at the edges thereof, this of course secures the outer edges of the several folds or plies of paper, but leaves the inner angular edge 8 loose and unsecured to the body of the apron. As it is desirable to secure the body portions of these sections to prevent them from being accidentally caught on or by foreign objects of any kind with the possibility of injury to the apron, I prefer to secure them to the latter. This I do by running a line of stitching 9 through the sections 5 and adjoining apron at a point below the upper edge of the apron as shown. The reinforcing sections 5 as thus formed and secured in position give the apron added strength and stiffness at the upper waist line corners thereof which is sufficient to preserve its shape in normal use and adds substantially to the life of the apron.

As a feature of economy in the manufacture of the apron, the tie strings 2 are secured to the apron by the same lines of stitching 9 which are employed for securing the sections 5. In addition to this feature of economy in the securing of the tie strings by the lines of stitching 9, the securing of the tie strings opposite the sections 5 is also most important in that said sections provide a reinforcement of the apron at such point which prevents tearing of the same under the strain produced by the strings when tied about the wearer of the apron. Without such reinforcement it has been found in

practice that the apron readily cuts or tears 40 loose at the line of stitching employed for securing the tie strings.

What I claim is:

1. The method of making paper aprons, which consists in slitting the stock to define 45 the side edges of a bib and a depending skirt portion of greater width, folding the remaining cut material upon itself and upon the upper corners of the skirt portion to reinforce said corners, and thereafter securing 50 tie strings to the folded material by means passing through the string, folded material and skirt portion.

2. The method of making paper aprons, which consists in cutting the stock on parallel lines to provide a centrally disposed bib portion and a depending skirt portion of greater width, folding the cut material on each side of the bib portion into triangular shape upon the upper corners of the skirt 60 portion, and thereafter securing the triangular folded material to said corners by a line of edge stitching.

3. The method of making paper aprons, which consists in cutting the stock on parallel 65 lines to provide a centrally disposed bib portion and a depending skirt portion of greater width, folding the cut material on each side of the bib portion into triangular shape upon the upper corners of the skirt 70 portion, securing the triangular folded material to said corners by a line of edge stitching, and thereafter securing tie strings to said corners by a line of stitching uniting 75 said strings, triangular folded material and skirt portion.

In testimony whereof I affix my signature.
MORRIS KATZ.
